US0D1079749S

(12) United States Design Patent (10) Patent No.: US D1,079,749 S
Hanada (45) Date of Patent: * Jun. 17, 2025

(54) DISPLAY SCREEN WITH GRAPHICAL USER INTERFACE

(71) Applicant: Airbnb, Inc., San Francisco, CA (US)

(72) Inventor: Alana Lima Hanada, San Francisco, CA (US)

(73) Assignee: Airbnb, Inc., San Francisco, CA (US)

() Term: 15 Years

(21) Appl. No.: 29/868,014

(22) Filed: Nov. 16, 2022

(51) LOC (15) Cl. 14-04

(52) U.S. Cl.

USPC D14/486

(58) Field of Classification Search

USPC D14/485-495

CLAIM

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design.

1 Claim, 1 Drawing Sheet
